STRATFORD B. ALLEN, OF CAMBRIDGE, MASSACHUSETTS.

RECEPTION APPARATUS FOR TELEPHONE SYSTEMS.

Application filed February 21, 1924. Serial No. 694,271.

This invention relates to devices for conveniently applying means for producing an alternating potential and eliminating the passage of direct or uni-directional current to the phones. In some telephone systems, especially those employing thermionic tubes, such, for example, as radio receiving apparatus, amplifiers and the like, the passage of the high potential or plate current through the phones causes damping of the diaphragm vibrations; and in instances where care is not observed in connecting the phones with due regard for polarity, de-magnetization of the field magnets often occurs. Further, distortion of the incoming signal is a common occurrence under such conditions, especially in cases where there is no provision for regulating the distance between the pole pieces and diaphragm of the receiver, such distortion being electromechanical in origin.

While my invention is generally applicable to telephone receiving systems where direct or pulsating direct current is applied to the receiver, and under other varying conditions of service, it is especially adaptable for use in connection with radio receiving apparatus, amplifiers and the like wherein reception and amplification are brought about by means of thermionic tubes having the receiver connected in the plate circuit; though I would have it expressly understood that I in no wise limit myself to this specific embodiment or application of my invention, which I have selected as a basis for illustrating and describing my invention.

My invention broadly comprises the provision and arrangement of means, so arranged as to be contained within the shell of a telephone plug or its equivalent, for preventing the passage of direct or pulsating direct current, and for converting such pulsating currents into alternating or biased alternating current, in the telephone or loud speaker circuit.

I have found that many of the troubles inherent in certain types of telephone and amplifying systems, especially with respect to radiophone reception, originate in the damping or de-magnetizing effects of direct current, often producing "foggy" tone, faulty articulation, and "rattle" of the receiver diaphragm upon reception of loud or powerful signals. In the case of de-magnetization there occurs a gradual weakening of reception as time goes on which is in many cases

attributed to other parts of the apparatus. It is the object of the present invention to provide an effective means capable of easy and convenient application by a technically unskilled user of radio apparatus, for eliminating such conditions, inimical to the satisfactory performance of telephone receivers, among which of course are included the variety known as "loud speakers".

I shall describe certain illustrative embodiments of my invention and then point out with more particularity the essential elements of novelty in the annexed claims. It is intended that the patent shall cover in the appended claims, whatever features of patentable novelty exist in the invention disclosed.

In the drawings:

Figure 1 is a diagrammatic sketch of one embodiment of the invention showing a thermionic tube amplifier with a wiring diagram of my invention attached thereto.

Figure 2 is a side elevation of a telephone connection plug, the shell of which contains the impedance coil and condenser shown diagrammatically in Figure 1;

Figure 3 is a vertical section on the line 3-3 of Figure 2, showing the impedance coil and condenser mounted and connected within the shell, and the general arrangement of terminals for interposing them in connective relation between the amplifier and the telephone receiver.

Fig. 4 is a diagrammatic sketch of another embodiment, attached to a thermionic tube as in Figure 1;

Figure 5 is a side elevation of a connection plug whose shell contains the resistance and condenser shown diagrammatically in Figure 4;

Figure 6 is a vertical section on the line 6-6 of Figure 5 showing contents of the shell.

The drawings illustrate my invention in connection with an amplifying system such as is ordinarily employed in the reception of radio signals by telephone. 1 is a vacuum or thermionic tube of the usual or any suitable type, which ordinarily is connected to a telephone receiver 6' at its input points *a* and *b*. The vacuum tube 1 in the present instance is operated by the A battery 2, supplying current to its filament 3, and the B battery 4 of higher potential supplying current to its plate 5 and telephone receiver 6.

- In the present common practice in radio telephone reception and amplification the plate circuit has terminal points *a* and *b* to which the telephone is connected as at *6'*, as shown 5 by the dotted lines in Figure 1. Since this description is concerned only with the immediate or local conditions to be met in the telephone receiver circuit *a b*, in which the plate 5 and the B battery 4 are integral parts, 10 the specific arrangement of the grid 7 and the tube input circuit *c d* is to be regarded in this description merely as indicating suitable means whereby the plate circuit and telephone input *a b* is influenced and actuated. 15 When phones 6' are connected as shown in dotted lines, the plate current passes through the phones as direct or pulsating direct current according to the operation or excitation of the grid 7 in connection with its input 20 circuit *c d*. Such passage of direct current either tends to energize the pole pieces of the phones 6' further, with greater pull or damping load on their diaphragms, and consequent distortion of the signal received, or, in cases 25 where the phone terminals are connected at *a* and *b* in reverse magnetic relation to the phone magnets, produces a weakening of the field generated from the pole pieces of the phones 6', considerably to the detriment of 30 efficient reception. Under high potential of the B battery 4, this may eventually cause permanent weakening or de-magnetization of the permanent field magnet of the telephone receiver. And even receivers having a separately excited field are impeded in their action 35 by the damping load effect on the diaphragm arising from the passage of direct current through such receiver.

My invention provides a means for eliminating the passage of direct current through the phones by arranging them as at 6, and by combining therewith a condenser 9 and an impedance coil 8 (Fig. 3) or preferably a fixed resistance 48 (Fig. 5), all arranged 45 within the shell of the connecting plug 10, so as to afford easy and simple attachment between the phones 6 and the plate circuit *a b*. The phones 6 are connected as shown diagrammatically in Figures 1 and 4 by the 50 full lines, in series with the capacity 9 which serves as a stoppage condenser to prevent flow of direct current through the phones 6. The condenser 9 and the phones 6, arranged in series as described, are connected across the 55 impedance coil 8, or the fixed resistance 48 (i. e. are shunted across its terminals *e* and *f*); and the impedance coil 8, or the resistance 48, is connected in the plate circuit in series with the B battery 4 and the plate 5 of the vacuum 60 tube 1, conducting the direct current between *a* and *b* where the telephones have usually hitherto been connected as indicated at *6'*.

Referring now especially to Figures 1-3, upon excitation of the grid 7 of the tube 1,

the plate current will fluctuate accordingly, 65 and the blocking action of the impedance coil 8 in the circuit *a b* will then operate to charge and discharge the condenser 9, according to the frequency of the fluctuations in the plate circuit current. Thus, an alternating voltage will be produced between the terminals *e* and *f* of the impedance coil 8; and the phones 6 shunted across the coil, in series with the condenser 9, produce audible signals by reason of the transfer of fluctuating or alternating potentials between the elements of the condenser 9, with the resultant passage of alternating currents through the phones 6. Thus a condition is created whereby the phones 6 do not sustain passage of the direct current in the plate circuit *a b*, but respond only to alternating potentials caused by fluctuations in said direct current. In this manner and by the means aforesaid are damping and de-magnetizing loads 70 eliminated; and freer and less impeded diaphragm action of the phones 6 is brought about. As a result better articulation of the received signal is obtained; closer regulation of the distance between the pole pieces and 75 diaphragms of the phones 6 is made possible; and, in certain instances, increased volume of reception is obtained through the ability to increase the load applied to the co-acting thermionic amplifier or vacuum tube 1, where 80 previously such increased load would have produced distortion of the audible signal. 90

An important feature of my invention in the described form is that it is so constructed as to be easily attachable without technical knowledge, as a unit, to existing systems, being so organized as to form an integral part of the connecting plug. Referring to Figure 3, the shell 11 of the plug contains the impedance coil 8 and condenser 9 suitably connected to the electrodes 12 and 13, which are insulated each from the other by the insulating bushings 14 and 15, and are in the form common in standard practice and attachable to the usual type of jack now employed in radio and telephone apparatus. In this construction the inside terminal *f* of the coil 8 is connected to the core 16 which acts as a conductor between the electrode 12 and the telephone binding post 17 through the 100 clamping screw 18 and the offset support 19 for the said binding post 17, the clamping screw 18 and offset support 19 being insulated from the cup 21 by the insulating bushings 22 and 23. Provision is made for attaching the other terminal of the telephone receiver by the binding post 20 attached to the cup 21 which in turn is connected to one 105 element of the condenser 9. The said telephone receiver's portion of the circuit is completed by means of the remaining and opposite element of the condenser 9, which is attached to the outside terminal *e* of the wind- 110 115 120 125

ing of the coil 8, thence making contact to the electrode 13 through the supporting cap 24.

In its construction the coil 8 comprises an iron core 16 having attached at each end annular insulators 25 and 26 which serve as the supporting and centering members for the insulating tube 27 upon which the condenser 9 is mounted. Suitable terminals *e* and *g* are provided in the condenser 9 as means for attaching its respective elements to one end *f* of the coil 8 and to the binding post 20, the connection *g* therethrough being analogous to the point *g* connecting with the phones 6, as shown diagrammatically in Figure 1. Thus there is combined an impedance coil 8 having an iron core 16, and a condenser 9, as integral parts of one apparatus unit, applicable in the usual manner of a telephone plug, to existing systems of radio reception, without it being necessary for the user to understand the relations or action of the same; and a sealed closure 28 may be provided to keep people from getting at the screw 18.

Figures 4, 5 and 6 illustrate a form of the invention which is preferred on account of simplicity of construction; lower cost of manufacture; adjustability; equal or superior efficiency; and other advantages. In this form a fixed resistance 48 takes the place of the impedance coil 8 and its core 16, a simple support 56 being substituted to perform the structural function of the core. The resistance is preferably equal to or greater than the internal impedance or resistance of the thermionic tube. There is a considerable drop of electromotive force between the terminals of a high resistance 48 thus inserted in the plate circuit. The fluctuations of resistance or impedance in that part of the plate circuit which is in the thermionic tube, cause the variations of current which it has been customary to pass through the phones. The arrangement shown in Figure 4 takes advantage of the fact that a change of impedance in the tube changes the I R drop, or drop of electromotive force, between terminals *e*, *f*, of the fixed resistance 48. As the condenser circuit 9 is in parallel with this resistance there is a fluctuation in the condenser circuit whenever the current in the plate circuit fluctuates; and this condenser fluctuation results in alternations of current which can be heard if telephones are inserted therein as at 6.

The practical embodiment of the diagrammatic fixed resistance 48 of Figure 4 is illustrated in Figure 6 at 48 as a high resistance carbon disk. A simple construction is to make this of India ink absorbed into a blotter, dried and compressed. Obviously it can be made otherwise; but this is easy and notably inexpensive, and when made as a washer is capable of having its resistance

varied until the desired value is attained, by merely compressing it with a screw. It is observed in this connection that the resistance does not change appreciably after a certain degree of compression has been reached. If made of a value ranging from 25,000 to 75,000 ohms no difference in results has been detectable, in experiments which I have carried out.

In this arrangement the I R drop across the fixed resistance produces less loss than the iron and copper losses in ordinary impedance with equal volume of signal.

With thermionic tubes such as are in common use for radio reception the resistance 48 has been found to give satisfactory results when fixed at a value of 20,000 to 60,000 ohms. In the case of a reactance or the primary of a transformer, the impedance of the transformer or coil has been found to produce good results when equal to approximately 40,000 ohms at 1000 cycles, which is the rate commonly in use for testing apparatus at voice frequencies. For the condenser, a capacity successfully used ranges approximately from .025 to .1 microfarad.

It will be observed that the apparatus in each of the modifications mentioned is an accessory to the telephone arranged as a unit which can be handled separately and can conveniently be interposed exteriorly between the radio receiver, so called, and its phones, in which form it is well adapted for sale and distribution to those who already have their radio receivers. But the unit is not necessarily thus arranged and can be otherwise housed conveniently in connection with the telephone jack, or in substitution for it, in which latter case the sockets 17, 20, would be set for the convenient reception of the telephone cord tips.

I claim as my invention:

1. A telephone appliance comprising the combination, with a telephone plug, of a container mounted on the plug; an impedance located in the container and connected between the tip and sleeve elements of the plug; output terminals mounted on the container; and a condenser, through which one of the output terminals is connected in series to one end of the impedance, the other output terminal being connected to the other end of the impedance; the said output terminals being adapted for the connection to them of an external portion of the output circuit.

2. A telephone appliance comprising, in combination, a tubular shell; a telephone plug at one end thereof; telephone terminals at the other end; a centrally disposed core extending within the shell and coupling the said plug and terminals mechanically together; a resistance between said plug and said terminals, connected to receive current through the plug and by-pass it around the said terminals; and a condenser arranged around

the core within the said shell, and connected in series with one plug terminal and one telephone terminal.

3. A telephone appliance comprising, in combination, a tubular shell; a telephone plug at one end thereof; a terminal-carrying cup set in the other end; telephone terminals within the cup; a centrally disposed core extending within the said shell and coupling the plug and cup together; and a resistance within the shell connected to receive current through said plug and by-pass it around said terminals.

4. A telephone appliance comprising, in combination, a tubular shell; a centrally disposed core extending therethrough; a telephone plug screwed into the core at one end of said shell; telephone terminals at the other end of the shell; and a washer of compressible resistance material in circuit therewith and clamped between said core and said plug adapted for its resistance to vary according to the degree to which it is compressed by said clamping.

5. A telephone appliance comprising, in combination, an inner and an outer tubular

shell arranged to form an annular chamber between them; a telephone plug at one end of said shells; telephone terminals at the other end; a core extending within the inner shell and coupling said plug and said terminals together; a resistance at the base of said plug and in circuit with said plug and terminals; and a condenser arranged in said annular chamber and connected in series with one plug terminal and one telephone terminal.

6. Accessory apparatus for a telephone, comprising a shell with a condenser and high fixed resistance contained therein; heads closing the ends of the shell and a core sustained between said heads; and a telephone plug comprising insulated tip and sleeve input terminals projecting from said core; the said resistance being in the form of a washer connecting the base of said tip and sleeve; and output terminals connected in series with the condenser between said tip and sleeve.

Signed at Boston, Massachusetts, this thirteenth day of February, 1924.

STRATFORD B. ALLEN.
